FIG. 4

FIG. 5

UNITED STATES PATENT OFFICE.

LAURENCE SIBLEY CARLETON AND ROBERT GARDNER CARLETON, OF DAVENPORT,
IOWA.

TRAFFIC SIGNAL DEVICE.

1,311,755.

Specification of Letters Patent. Patented July 29, 1919.

Application filed December 3, 1917, Serial No. 205,158. Renewed June 17, 1919. Serial No. 304,920.

To all whom it may concern:

Be it known that we, LAURENCE S. CARLETON and ROBERT G. CARLETON, citizens of the United States, residing at Davenport, 5 in the county of Scott and State of Iowa, have invented new and useful Improvements in Traffic Signal Devices, of which the following is a specification.

Our present invention pertains to traffic 10 signal devices for use on automobiles; and it contemplates the provision of a simple and efficient apparatus through the medium of which an automobile driver is enabled to apprise drivers behind him as well as the 15 traffic officer in front of him of his intentions respecting the movements of the automobile.

To the attainment of the foregoing the invention consists in the peculiar construction, novel combinations and adaptation of parts, as hereinafter described and definitely claimed.

In the accompanying drawings which are hereby made a part hereof:

25 Figure 1 is a side elevation showing a portion of an automobile equipped with our novel device.

Fig. 2 is an enlarged, detail view showing the signal arm by dotted lines in its extended position and by full lines in its idle position.

30 Fig. 3 is a detail section taken on the line 3—3 of Fig. 2.

Fig. 4 is an edge elevation of the device.

35 Fig. 5 is a section, taken on the line 5—5 of Fig. 2.

Fig. 6 is an enlarged detail section illustrative of the actuating device employed on the automobile dash.

40 Similar numerals of reference designate corresponding parts in all the views of the drawings.

Among other elements our novel signal device comprises a casing body 1, preferably of aluminum, and provided with a back closure plate 2 on which is a mirror 3, designed to enable the driver to see back of the machine. The said casing body 1 is hollow and is fixed in transverse position above 45 the left-hand fender 4 of an automobile, as shown in Figs. 1 and 5. The said fixture is effected through the medium of a forwardly extending arm 5 on the casing body, which arm 5 is adjustably fixed at 6 to a standard 50 7, fixed to and rising from the fender. In

the outer edge of the casing body 1 is an opening 8, Fig. 2, sufficiently large for the free play of the signal arm 9, best shown in Figs. 2, 3 and 5. The said signal arm comprises an outer portion, which is preferably though not necessarily of general circular form, Fig. 2, and a shank 10 on the said outer portion; the said shank being pivoted at 11 in the casing body and being provided with an angularly-disposed arm 12, for a purpose hereinafter set forth.

On its forward side the outer portion of the arm 9 is designed to bear the word "Turn" or a word of similar import, designed to inform a traffic officer that it is the intention of the driver to turn at a crossing, and on the rear side of said outer portion 9 the word "Stop" or a word of like meaning is provided, designed to convey the intention of the driver to the operators of following vehicles. With a view to attracting the attention of persons in front of and in the rear of the automobile to the signal arm 9 at night, we provide an incandescent lamp 13 which is arranged to illuminate both sides of the arm 9, as best shown in Fig. 3, and on both sides of the said arm 9 we provide reflecting flanges 14, designed to throw the light downwardly on the arm sides. We also provide on the said flanges 14 depending guards 15, disposed in front and rear of the lamp and equipped with red glasses 16 so that a red light will be displayed at each side of the signal arm.

Fixed to and extending between the casing body 1 and the dash 17 of the automobile is a flexible tube 18, of suitable material, a portion of which extends in the casing body as shown in Fig. 2 and is clamped or otherwise suitably fixed thereto. Through 90 the said tube extends a steel wire 19 through the medium of which the signal arm 9 is actuated. This wire 19 is connected at one end to the angularly-disposed portion 12 of the signal arm, and is carried through the tube 18 and is connected at its opposite end to the plunger 20 of the actuating device best shown in Fig. 6, the connection being preferably effected by extending the wire and the tube 18 into the plunger and securing the wire to the plunger by set screws 21. The said plunger 20 is provided with a finger ring 22 at its rear end, and is disposed and movable in a casing 23. The tube 18 is retained in the casing by the 100 105 110

tube enlargement 18^a, and the plunger is removable on the tube portion within the casing. The casing 23 is fixed to the dash 17 and serves to effect connection of the tube 5 18 to the dash.

By virtue of the mechanism thus far described, it will be manifest that when the automobile driver pulls rearwardly on the plunger 20, the signal arm 9 will be swung 10 from its pendent position within the casing body 1 to the extended position shown by dotted lines in Fig. 2, while when the driver releases the plunger 20, the arm 9 will gravitate back to its idle position within the 15 casing body 1.

The filament of the incandescent lamp 13 is electrically connected as indicated by 30 with a terminal 31 arranged on and insulated from the signal-arm portion 12. The 20 said terminal 31 is designed when the arm 9 is swung upwardly and outwardly to make contact with a complementary terminal 32 arranged in the upper portion of the casing body 1, which terminal is connected through 25 wire 33 with one pole of a battery 34 carried in a box on the forward side of the body 1. The other side of the electric circuit is grounded to the casing body 1. Thus when the arm 9 is caused to assume the position 30 shown by dotted lines in Fig. 2 the terminal 31 will be carried into contact with terminal 32, and the filament of the lamp will be caused to glow, while when the arm 9 gravitates back into the casing body, the terminal 31 will be carried out of contact with terminal 32 and the supply of current to the filament of the lamp will be interrupted.

To save current in the daytime a switch 34 is provided.

40 It will be gathered from the foregoing that our novel signal device is simple and efficient, and that its arrangement on an automobile is calculated to enhance rather than detract from the finished appearance 45 of the latter.

Having described our invention, what we claim and desire to secure by Letters Patent, is:

1. A traffic signal device for automobiles 50 comprising a hollow casing supported at the front portion of the automobile and provided with an opening in its outer edge, a signal arm pivoted within the casing adapted to swing out of and into said casing and 55 having a transverse opening formed through

the peripheral portion of said signal arm, reflecting flanges mounted on both sides of said arm, a lamp disposed within said opening with portions extending under the flanges, a depending guard disposed in the 60 front and the rear of said lamp, whereby the lamp will throw the light downwardly and illuminate substantially the entire area of both faces of the arm at the same time.

2. A traffic signal device for automobiles 65 comprising a hollow casing supported at the front portion of the automobile and having an opening in its outer edge, a signal arm pivoted within the upper portion of the casing adapted to swing out of and into said casing and having a transverse opening therethrough, reflecting flanges mounted on both sides of said arm, a lamp disposed within said opening, a depending guard disposed in the front and the rear of said lamp, 70 each guard being equipped with a red glass so that a red light will be simultaneously displayed at each side of the said signal arm.

3. A traffic signal for automobiles comprising a hollow casing supported near the 80 front portion of the automobile and having an opening at its outer edge, a signal arm pivoted within the casing adapted to swing out of and into said casing and pivoted to an integral shank at its upper end, said shank 85 having an integral extension at right angle thereto, in combination with a tubular casing arranged longitudinally of the automobile and fixedly secured through the dash thereof, a flexible tube extending into the upper portion of said hollow casing provided with an integral enlargement fitted against an annular extension formed within the tubular casing, a movable plunger within said tubular casing surrounding said tube 95 and a flexible wire secured at one end to said plunger and its opposite end fixedly secured to the outer end portion of the integral extension at right angle to the signal arm and within the upper end of the first named 100 casing.

In testimony whereof we have hereunto set our hands in presence of two subscribing witnesses.

LAURENCE SIBLEY CARLETON.
ROBERT GARDNER CARLETON.
